UNITED STATES PATENT OFFICE.

PEIRCE VAN VLECK AND HOWARD COOPER, OF BALTIMORE, MARYLAND, ASSIGNEES
TO WILLIAM H. PEIRCE, OF BALTIMORE, MARYLAND.

ENGINE.

1,385,027.

Specification of Letters Patent. Patented July 19, 1921.

Application filed May 22, 1920. Serial No. 383,482.

To all whom it may concern:

Be it known that we, PEIRCE VAN VLECK and HOWARD COOPER, citizens of the United States, residing at Baltimore city, in the 5 State of Maryland, have invented certain new and useful Improvements in Engines, of which the following is a specification.

This invention relates to engines and more particularly to a double acting single ex- 10 pansion type.

The objects of the invention are: First, to construct an engine of the general class indicated in which all valve gear is eliminated and the valve distributing the fluid pressure 15 on either side of the piston is actuated by the same fluid reciprocating the piston. Second, to construct and arrange the valve distributing the fluid pressure with respect to the chest and its relation to the cylinder, so that 20 no stuffing boxes or glands are necessary for the elements connecting or controlling said valve with the movements of the piston.

Third, to construct and arrange ports in the distributing valve and the chest in which 25 said valve reciprocates and oscillates, so that the motive fluid reciprocating the valve is efficiently and positively controlled, thereby insuring the constant and uniform operation of the motor or engine. Fourth, to so construct and arrange the cylinder, chest, valve 30 with their cooperating ports and the connection of the reciprocating piston with the valve, whereby the engine can be cheaply manufactured and all the parts are readily 35 accessible, easily assembled or taken apart and inspected or repaired with a minimum of cost and time.

Fifth, other advantages and objects of the invention will appear from the detailed description of the construction and operation 40 of the invention to be hereinafter given.

The invention consists of structural characteristics and relative arrangement of elements which will be hereinafter more fully 45 described and particularly pointed out in the appended claims.

In the drawings, in which similar reference characters indicate the same parts in the several figures,

50 Figure 1, is a longitudinal section partly in elevation of the motor;

Fig. 2 is a fragmentary section on line II—II of Fig. 1;

55 Fig. 3, is a similar section on line III—III of Fig. 1;

Referring to the drawings, 10 is the cylinder having a double acting piston 11 connected to a tubular piston rod 12 passing through a stuffing box 13 in the head 14. Said piston rod 12 may be connected to any suitable pump, compressor, or other mechanical expedient, not shown, and forming no part of the present invention, to which the power of the motor is to be applied. The head 15 of the cylinder is so cored and constructed 60 as to form a chest 16 in which is provided a combined oscillatory and reciprocatory distribution piston valve 17 having end cylindrical sections 18 and 19 and a central cylindrical section 20, said chest 16 being 70 provided with the usual liner 21, and heads 22 and 23 secured in any well known manner and forming no part of the present invention. In the head 15 are cored a series of ports 24, 25, 26, 27 and 28 which communicate with properly spaced and arranged openings through the liner 21, into the chest 16, as indicated, said port 24 having opening 29, port 25, opening 30, port 26 openings 31, 31', 32 and 33, central port 80 27 opening 34, and upper port 28 openings 35, 36 and 37. The other ends or openings of the ports 24, 25 and 26 are in communication with the ports 38, 39 and 40 cast in the cylinder 10, as shown for purposes to 85 be presently described. The cylindrical section 18 of the distribution valve 17 is provided with two short longitudinal ports 41 and 42 which are adapted to connect one end of the chest 16 with the openings 35 and 90 31 of the ports 28 and 26 respectively, while the ports 43 and 44 in the other cylindrical section 19 of the valve 17 connect the other end of the chest 16, respectively with the openings 37 and 33 communicating with the 95 ports 28 and 26, as will be readily seen from the drawings. Passing through the cylindrical section 19 of the valve 17 with a tight fit is a pin 45, one end of which is suitably threaded at 46, as shown, while its other end is adapted to be firmly seated in a socket 47 formed in the central cylindrical section 20 of the valve 17, said pin 45 being slidably and loosely connected to the upper end 100 of a rod 48 passing with considerable clearance through the port 27 as shown. The other end of the rod 48 is adapted to pass within the hollow section of the piston rod 12 and its lower end 49 and enlarged upper end are engaged by the under and upper 105

110

sides respectively, of the tappet plate 50 secured to the upper side of the piston 11 during the reciprocation of said piston 11 and its rod 12, for the purpose of oscillating the valve 17 and thereby properly admitting the live motive fluid to either end of the chest or exhaust the entrapped fluid therefrom to reciprocate said valve 17 for purposes to be presently explained.

10 The operation of the invention is as follows:

The parts being in the position as shown in Fig. 1, the live motor fluid enters the port 38 and passes through opening 29 into chest 16 and through opening 34 and port 27 around valve rod 48 into the cylinder 10 and forces the piston 11 in a downward direction as indicated by the arrow, and the expanded motive fluid on the other side of the piston passes through ports 39, 25, openings 30 and 31', ports 26 and 40, to a condenser, not shown, or atmosphere. As said piston 11, approaches the end of its downward stroke, the tappet plate 50 engages the enlarged end 49 of the valve rod 48 and partially rotates the valve 17 so that the port 41 in the cylindrical section 18 registers with the opening 35 of the port 28 and shuts off the port 42 with opening 31 of port 26 and 15 exhaust port 40, and port 43 of section 19 is cut off from opening 37 and port 28 and port 44 is in communication with opening 33 and ports 26 and 40, thereby enabling the entrapped motive fluid to escape to the 20 atmosphere. The valve 17 being in this partially rotated position, live motive fluid then passes through the port 24, openings 29 and 36 into port 28, opening 35, and port 41 back of section 18 and throws the valve 17 25 to the other end of the chest 16, when the section 18 closes opening 31', and section 19 uncovers opening 32 and section 20 passes to the right of opening 29.

The valve being in this thrown and last 30 described position, the live fluid pressure is enabled to take the course through the ports 38, 24, opening 29 into chest 16, opening 30, ports 25 and 39, into the cylinder, to force the piston 11 upwardly or return stroke, and 35 the motive fluid on the upper side of piston and within the cylinder 10 passes out by way of port 27, opening 34, chest 16, opening 32, ports 26 and 40 to the atmosphere. The piston 11 on reaching the end of this stroke, 40 the lower end of the hollow section of the rod 12 engages the enlarged end 49 of the valve rod 48 or upper side of tappet plate 50 engages the lower end of the upper enlarged portion of valve rod 48 and partially and 45 reversely rotates the valve 17 into the position shown in Fig. 2, so that the port 41 is cut off from communication with opening 35 and port 28, port 42 communicates with opening 31, and port 43 is in communication 50 with opening 37 and port 28 and port

44 is cut off from opening 33 and port 26. In this position of the valve 17, the live motive fluid passes through ports 38 and 24, openings 29 and 36, port 28, opening 37, port 43, into the chest back of section 19 and the motive fluid back of section 18 escapes to the atmosphere by way of port 42, opening 31 and ports 26 and 40, when the valve 17 is returned to the position shown in Fig. 1, and the cycle of operation just described is repeated.

It will be seen that owing to the short length of the ports 42 and 44, the openings 31 and 33 are cut off sufficiently early to effect a cushioning of the endwise travel or 80 reciprocation of the valve 17, and the cushioning of the piston 11 is effected by providing that the movement of the valve 17 be such as to reverse or admit live motive fluid pressure in the cylinder 10 just before 85 said piston 10 reaches the end of its stroke. The valve 17 may also be so arranged to be completely balanced so far as circumferential pressures are concerned by arranging the ports in said valve in equal and opposite pairs and so disposed, to communicate with the ports and openings in the cylinder and chest, thereby equalizing the pressure at all times on the opposite surfaces of the valve and insuring it to positively reciprocate under all conditions or service.

From the foregoing disclosure of the construction, arrangement, assembling and mode of operation of the motor, it will be seen that all the objects and advantages recited in the statement of invention are fully and efficiently carried out and while one embodiment of such an arrangement is herein illustrated and described, it will be readily seen that many changes will readily suggest 100 themselves to any one skilled in the art without departing from the structural characteristics and relative arrangement of elements covered by the claims.

110 What we claim is:

1. A non-rotative motor comprising a cylinder, a piston reciprocating within said cylinder, combined live fluid and exhaust ports leading to opposite ends of the cylinder, a live fluid pressure port and an exhaust port, a chest at one end of the cylinder and having a series of openings communicating with the live pressure and exhaust ports and ports leading to the opposite ends of the cylinder, a combined oscillating and fluid actuated reciprocating distributing valve within said chest and having ports so constructed and arranged to cooperate with said series of openings communicating with the live fluid pressure exhaust ports and ports leading to the opposite ends of the cylinder to admit live fluid pressure on opposite sides of the piston to reciprocate said piston and exhaust said fluid from the cylinder and admit live fluid 125 130 135 140 145 150 155 160 165 170 175 180 185 190 195 200 205 210 215 220 225 230 235 240 245 250 255 260 265 270 275 280 285 290 295 300 305 310 315 320 pressure within the chest and on each end of the distributing valve and exhaust said fluid from the chest, and a single valve rod whose axis is eccentrically arranged with respect to the axis of the valve and actuated by the reciprocation of the piston and freely passing through the port leading into the cylinder at the end nearest to the chest for oscillating said reciprocating distribution valve and without in any way obstructing the passage of the live fluid into or exhaust of expanded fluid from the cylinder.

2. A non-rotative motor comprising a cylinder, a piston reciprocating within said cylinder, combined live fluid and exhaust ports leading to opposite ends of the cylinder, a live fluid pressure port and an exhaust port, a chest at one end of the cylinder and having a series of openings communicating with the live pressure and exhaust ports and ports leading to the opposite ends of the cylinder, a combined oscillating and fluid actuated reciprocating distributing valve within said chest and having ports so constructed

and arranged to coöperate with said series 25 of openings communicating with the live and exhaust ports and ports leading to the opposite ends of the cylinder to admit live fluid pressure on opposite sides of the piston to reciprocate said piston and exhaust 30 said fluid from the cylinder and admit live fluid pressure within the chest and on each end of the distributing valve and exhaust said fluid from the chest, a pin attached to the valve and arranged parallel to and to 35 one side of the longitudinal axis of said valve, and a valve rod having one of its ends slidingly connected to said pin and freely passing through the port leading into the cylinder at the end nearest to the chest 40 and intermittently actuated by the reciprocation of the piston without obstructing the admission of live fluid into or exhaust or expanded fluid from the cylinder.

In testimony whereof we affix our signatures.
